KEY CASE

Filed Aug. 1, 1930

Inventor:
George E. Prentice
By his wife, Lillian M. Wombley
Attest:

UNITED STATES PATENT OFFICE

GEORGE E. PRENTICE, OF BERLIN, CONNECTICUT, ASSIGNOR TO G. E. PRENTICE MANUFACTURING COMPANY, OF NEW BRITAIN, CONNECTICUT, A CORPORATION OF CONNECTICUT

KEY CASE

Application filed August 1, 1930. Serial No. 472,284.

This invention relates to key holders of the type customarily having an enclosing body of flexible material and a plurality of key retaining members pivotally mounted so that they may be enclosed within the casing or swung outwardly therefrom to permit insertion and rotation of a key within a lock without twisting the entire case. The invention pertains more particularly to improvements in the rotatable anchors by which the key hangers are connected to a metal plate secured to the casing, and has for its principal object the provision of anchor members which are easy and economical to manufacture and which substantially reduce the cost of manufacture without sacrifice of operative efficiency.

A recommended embodiment of the invention is illustrated in the accompanying drawings, in which:

Fig. 1 is a front view of an opened key case equipped with the improved anchor members;

Fig. 2 is an enlarged section on line 2—2 of Fig. 1;

Figs. 3 and 4 are detail views illustrating a preferred mode of forming the anchor members; and

Fig. 5 is a view similar to Fig. 2 showing a modified form of the metal plate.

In the particular embodiment chosen for the purpose of illustration, the key case comprises in general a flexible casing of leather, fabric or the like, consisting of a back portion 6 and a pair of side flaps 7 and 8 adapted to fold over the central portion 6 and to be detachably secured as by a two part snap fastener indicated at 9 and 10; a sheet metal plate 11 fastened to the back 6 as by eyelets 12 or the like, and having its upper margin rolled into a semi-tubular, anchor-retaining portion 13 which is provided with spaced slots 14; and a plurality of key hangers 15 of usual construction carried by anchor members 16 swiveled for rotation and sliding movement in the slots 14. The particular construction and arrangement of the casing, the plate 11 or the hangers 15 are not essential to this invention, and may take any of several suitable and well-known forms, as de-

sired. For example, as shown in Fig. 5, the anchor-retaining portion 13' of the plate 11' may be rolled into substantially tubular form, and the slots 14' may extend to the extreme end of the plate instead of stopping short of said end as indicated in Fig. 2.

The improved anchor members 16 which constitute the principal feature of my invention are preferably made by simple forming operation from a common metal rivet having a countersunk head 17 and a split shank providing legs 18. Such an article is very inexpensive to manufacture in quantities and easily worked in shaping dies to produce a finished anchor which may assume a variety of shapes and sizes, as desired. In accordance with this invention, I preferably bend the legs into the form of an eye, as shown at 19 in Fig. 4, by means of a half ball die, the ends of the legs being brought into abutting relation. The anchor thus formed may be readily inserted in the slots 14 with the head 17 pivotally mounted within the retaining tube 13, and the key hanger 15 may be quickly and easily attached by threading it through the eye 19. It is apparent, however, that the legs 18 may be bent together through a loop or eye of the key hanger; and this mode of application is customary when the loop of the hanger is non-resilient.

It has been found that the use of my improved anchor members in place of the relatively expensive anchors heretofore employed, for example, the anchor members shown and described in the Biehl Patent No. 1,418,059, dated May 30, 1922, results in a saving of approximately fifty per cent in the cost of manufacturing the key case. It will be understood that the surfaces of the metal parts are usually nickel-plated, and it will be apparent that the improved anchor members are compact and neat in appearance and work easily and smoothly while the case is in use.

It should be understood that the present disclosure is for the purpose of illustration only and that this invention includes all modifications and equivalents which fall within the scope of the appended claims.

I claim:

1. In a key case, an anchor member consisting of a split metal rivet having its legs shaped to enclose an eye opening for the 5 reception of a key hanger.
2. In a key case, an anchor member consisting of a common split rivet having its head countersunk and its leg portions bent away from each other and then toward each 10 other so that the leg ends are in abutting relation, thereby to provide an eye for the reception of a key hanger.

Signed by me at Berlin, Connecticut, this
30th day of July, 1930.

15 GEORGE E. PRENTICE.
